FOR LIGHTERS AND ILLUMINATING BURNER

Fredrick H. Bowers, Kalamazoo, Mich.

Application October 3, 1956, Serial No. 43,212

Term of patent 14 years

(Cl. D48—27)

Figure 1 is a perspective view of a combination disposable fuel container for lighters and illuminating burner, showing my new design, being taken generally from the front.

Figure 2 is a top view thereof.

Figure 3 is a front side elevation of the same.

Figure 4 is an edge elevational view looking to the left as viewed in Figure 3, and

Figure 5 is an edge elevational view looking to the right as viewed in Figure 3.

I claim:

The ornamental design for a combination disposable fuel container for lighters and illuminating burner, substantially as shown.
